CLAIM

The ornamental design for an inflatable sofa, as shown and described.

DESCRIPTION

FIG. 1 is a top, front and right side perspective view of an inflatable sofa, showing my new design;
FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion labeled "9" in FIG. 2.

The dotted broken lines in FIG. 2 and FIG. 9 illustrate the border of the enlarged detailed view and form no part of the claimed design.

1 Claim, 9 Drawing Sheets(56)
